UNITED STATES PATENT OFFICE

116,953

DESIGN FOR A MASK FOR PHOTOGRAPHIC TEST STRIPS

Artemas Jean Haynes, New York, N. Y.

Application July 21, 1939, Serial No. 86,167

Term of patent 3½ years

To all whom it may concern:

Be it known that I, Artemas Jean Haynes, a citizen of the United States, residing at New York city, in the county of New York and State of New York, have invented a new, original, and ornamental Design for a Mask for Photographic Test Strips, of which the following is a specification, reference being had to the accompanying drawing, forming part thereof,

The figure is a three quarter view of a photographic test strip mask, showing my new design.

I claim:

The ornamental design for a mask for photographic test strips, as shown.

ARTEMAS JEAN HAYNES.
